CLAIM

The ornamental design for a set of interlocking bottles, as shown and described.

DESCRIPTION

FIG. 1 is a perspective view of a set of interlocking bottles showing my new design;

FIG. 2 is a perspective view of one of the bottles shown separately to clearly disclose the rear wall that interlocks with the other bottle;

FIG. 3 is a rear elevation of FIG. 2;

FIG. 4 is a side elevation of the bottle shown in FIG. 2, the opposite side elevation is a mirror image thereto except for the screw threading on the bottle neck;

FIG. 5 is a front elevation of FIG. 2;

FIG. 6 is a top plan view of FIG. 2;

FIG. 7 is a bottom plan view of FIG. 2;

FIG. 8 is a rear elevation showing one of the bottles of a second embodiment of the set of interlocking bottles that differs from the first embodiment only in the length of the vertical rib on the rear wall;

FIG. 9 is a side elevation of the bottle shown in FIG. 8, the opposite side elevation is a mirror image thereto except for the screw threading on the bottle neck;

FIG. 10 is a top plan view of FIG. 8;

FIG. 11 is a bottom plan view of FIG. 8;

FIG. 12 is a bottom plan view showing one of the bottles of a third embodiment of the interlocking bottle set that differs from the first embodiment only in the contours of the bottom surface; and,

FIG. 13 is a fragmentary bottom perspective view of FIG. 12, the portion of the bottle that is not disclosed is identical to the bottle shown in FIGS. 2 through 7.
